United States Patent Office.

JOHN S. CAMPBELL, OF NEWTON, NEW JERSEY.

Letters Patent No. 65,168, dated May 28, 1867.

IMPROVEMENT IN VEHICLES.

The Schedule referred to in these Letters Patent and making part of the same.

TO ALL WHOM IT MAY CONCERN:

Be it known that I, JOHN S. CAMPBELL, of Newton, Sussex county, New Jersey, have invented a new and useful Improvement in Vehicles; and I do hereby declare that the following is a full, clear, and exact description thereof, which will enable others skilled in the art to make and use the same, reference being had to the accompanying drawing, forming part of this specification.

This invention consists in making the body of a carriage or sleigh, as also the carriage-wheels or sleigh-runners, of hard rubber, in such a manner as to produce a durable and elegant carriage or sleigh, with comparatively little trouble or expense. In the annexed drawing my invention is illustrated—

Figure 1 being a longitudinal sectional elevation of my improved carriage; and

Figure 2, a transverse sectional elevation of the same.

Similar letters of reference indicate corresponding parts.

The body A of the carriage is moulded of India rubber, with the exception of the bottom *a*, which may be made of wood or any other suitable material. The seat B is also made of hard rubber, and provided with grooves so as to be held by the sides of the body. The body is provided with flanges *b b*, so as to secure the seat thereto with bolts and screws, as shown. Flanges *c c* are also arranged on the body to enable it to be more easily secured to the bottom *a*, as shown. The body A may be strengthened by cross-pieces *d d*, of which any number may be cast with it. It is obvious that ornaments of any desired kind may be readily produced in this manner, and a carriage or sleigh body of a high finish may be made almost as easy as a plain one. The rubber may also be colored, so that various tints may, if desired, be used. The wheels B may also be made of one solid piece of rubber, if desired, but they may be also made in various parts; the hubs and spokes being moulded together, and the felloes and tires applied afterward, which felloes may also be made of wood or other suitable material; or the whole wheel may be cast in one with the hub of wood or other material, as may be desired. The runners of sleighs may also be made of rubber and covered with metal. The bows, or all the solid parts of folding or stationary wagon tops, may also be made of hard rubber.

I claim as new, and desire to secure by Letters Patent—

1. The carriage or sleigh body A, when made of hard rubber, and provided with flanges *b* and *c*, and cross-pieces *d*, substantially as and for the purpose herein shown and described.

2. The running gear of wagons and sleighs when made of rubber, substantially as herein shown and described.

JOHN S. CAMPBELL.
